UNITED STATES PATENT OFFICE

2,375,123

COLLAPSIBLE BOX

Ralph S. McConnell, Portsmouth, Va.

Application April 29, 1943, Serial No. 485,053

1 Claim. (Cl. 217—15)

This invention relates to collapsible boxes.

An object of this invention is to provide a collapsible box which may be made out of either plywood or lumber, and which is so constructed and arranged that in collapsed form all of the parts are retained together so that the parts will not become lost during shipment.

Another object of this invention is to provide a collapsible box or receptacle including side, top, bottom and end walls which are all hingedly secured together, the opposite sides, top and bottom walls having metal bands secured thereto, and each band including hingedly connected sections with at least one section removable from the remaining sections so that the top wall may be either swung upwardly to an open position or may be completely detached to facilitate filling or emptying the box.

A further object of this invention is to provide a container of this type wherein the hinge barrels do not project outwardly of the adjacent walls of the container so that when the containers are stacked one upon another the upper containers will rest upon the bands of the lower containers, and the barrels of the hinges of one container will not damage the walls of an adjacent container.

A further object of this invention is to provide a container of this type which is capable of holding a considerable weight of material, with the material either loose or compressed, the container being so constructed that if the material is to be compressed the top wall may be completely removed and the container placed in a suitable form and press, and when the material has been compressed to the desired degree the top wall may be secured to the container.

A further object of this invention is to provide an improved means for retaining the end walls of the container in position, each end wall being coupled to the side walls by means of a pair of hinges having removable pintles, and each end wall being swingable inwardly against a side wall when the container is collapsed.

With the foregoing objects and others which may hereinafter appear, the invention consists of the novel construction, combination and arrangement of parts as will be more specifically referred to and illustrated in the accompanying drawings, wherein are shown embodiments of the invention, but it is to be understood that changes, modifications and variations may be resorted to which fall within the scope of the invention as claimed:

In the drawings:

Figure 1 is a detail side elevation of a collapsible box or container constructed according to an embodiment of this invention.

Figure 2 is an end elevation of the container.

Figure 3 is a vertical section taken longitudinally through the container.

Figure 4 is a sectional view taken on the line 4—4 of Figure 3.

Figure 5 is a fragmentary sectional view 10 through the top and one side wall.

Figure 6 is a fragmentary horizontal section taken substantially on the line 6—6 of Figure 3.

Figure 7 is a plan view of the container in collapsed position.

15 Figure 8 is an end elevation of a modified form of end wall, and

Figure 9 is a sectional view taken on the line 9—9 of Figure 8.

Referring to the drawings, the numeral 10 20 designates generally a container or box of collapsible form which is constructed of opposite side walls 11, a top wall 12, a bottom wall 13 and opposite end walls 14. The top, bottom and side walls are of like form and may be con-

25 structed of either plywood or lumber. These walls are constructed of a rectangular body 15 which has secured on the inner side thereof and

at the opposite ends a pair of transversely ex- 30 tends cleats 16. The cleats 16 are mitered at

their opposite ends as indicated at 17 so that when the container is in assembled condition, the ends of the cleats will abut against each other as shown more clearly in Figure 2. The cleats or bracing members 16 are adapted to be

35 secured to the wall 15 by means of nails or other suitable fastening members 18, and the cleats 16 form flanges or abutments against which the end walls 14 are adapted to engage. The end walls 14 are positioned innermost and, as shown

40 in Figure 2, the end walls may be formed with a plurality of openings 19 to permit air to enter the container.

The four walls, that is, the top, bottom and opposite side walls of the container are hingedly connected together by means of straps 20, 21 and 22. The straps 20 and 21 are end straps engag- 45

ing about the ends of the walls, whereas the strap 22 is an intermediate strap. The straps are of

like form and are constructed of a plurality of 50 hingedly connected sections 23, 24, 25 and 26.

The strap section 23 is secured across the end of the top wall 12 by means of clincher nails or

other suitable fastening members 27. The strap section 23 has secured to the opposite ends

55 thereof one portion 28 of a hinge structure.

The portion 28 includes inner and outer leaf members 29 and 30 having formed at their outer ends a hinge barrel 31. The adjacent end of the strap section 23 is interposed between the two leaf members 29 and 30 and firmly secured therebetween by means of a rivet or other fastening member 32. The opposite end of the strap section 23 also has secured thereto one portion 33 of a hinge which is similar in every detail to the hinge portion 28. The strap section 23 is substantially wider than the thickness of the cleat 16 which is secured to the top wall 12 on the inner side thereof, and preferably a nail or other fastening member 34 is extended through the hinge section 28 and clinched on the inner side of the top wall 12, as shown more clearly in Figure 5.

The strap section 24 comprises an elongated strap 35 which is secured by fastening members 36 to the outer side of the side wall 11 and the upper end of the strap 35 is interposed between inner and outer leaf members 37 and 38 forming a hinge section 39 correlated with the hinge section 33. The upper end of the strap 35 is riveted between the leaves 37 and 38 by means of a rivet 40, and a nail or other fastening member 41 secures the leaf section 39 to the adjacent portion of the side wall 11.

The lower end of the strap 35 is turned back or reverted as shown in Figure 2 thereby forming one portion 42 of a lower hinge member. The hinge section 42 includes an outer leaf 43, an inner leaf 44 and a hinge barrel 45. The two leaves 43 and 44 are riveted or otherwise secured together by means of a fastening member 46 and a nail or other fastening member 47 extends through the two leaves 43 and 44 and into the side wall 11. The barrel 45 has mounted therein a loop 48. The loop 48 also engages in a barrel 49 carried by a lower hinge section 50 which is secured to the bottom wall 13. The hinge section 50 forms an integral part of one end of the lower strap section 25 and is constructed in every detail similar to the hinge section 42.

The opposite end of the lower or bottom strap section 25 is also formed with a hinge portion 51, similar in every detail to the hinge portion 42. A loop 52 engages through the barrel 53 of the hinge portion 51 and also engages through the barrel 54 of an adjacent hinge member 55. The hinge member 55 is constructed integral with the lower end of the strap section 26 and is similar in every detail to the hinge member 42.

The upper end of the strap section 26 is secured between the inner and outer leaves 56 and 57 of an upper hinge section 58. A rivet or other fastening member 59 firmly secures the upper end of the strap section 26 between the leaves 56 and 57. The hinge sections 28 and 58 are detachably connected together by means of a removable pintle 60. As shown in Figure 2, the barrel 31 of the hinge section 28 engages in a cutout or recess 61 formed in the adjacent edge of the top wall 12. The barrel 62 of the hinge section 58 projects above the upper edge of the adjacent side wall 11 and projects inwardly into the recess 61 so that when the top wall 12 is coupled to the adjacent side wall 11 the hinge barrels 31 and 62 will not project above the top wall 12 or laterally of the adjacent side wall 11. The opposite edge of the top wall 12 is also cut out as indicated at 63 to receive the barrels of the hinge sections 33 and 39.

The end walls 14 are of like form and each is constructed of a polygonal wall member which

may be formed of either plywood or lumber. The end wall 14 is adapted to abut against the inner sides of the cleats or flanges 16, as shown in Figure 3. In order to provide for the ready collapse of the container and for the retention of the end walls 14 with an adjacent side wall, each end wall 14 is connected to the adjacent side walls by means of a pair of hinges 64. The hinge 64 includes one hinge section 65 which is secured by fastening member 66 to a side wall 11. A complementary hinge section 67 is secured by fastening members 68 to the inner side of the end wall 14. There are only two hinges for each end wall 14 and these hinges are disposed adjacent the upper edges of the end walls and the adjacent side walls.

The hinge sections 65 and 67 are detachably connected together by means of a removable pintle 69. Preferably the pintle 69 is substantially smaller in diameter than the inner diameter of the barrels of the hinge sections, thereby providing a slight play or movement permissible between the end wall 14 and the adjacent side wall 11. This play is desirable in view of the fact that when the container is in collapsed form, only one pintle 69 is removed from the pair of hinges on the end wall and the end wall is then swung inwardly against the inner side of the adjacent side wall.

In order to facilitate the swinging inwardly of the end wall 14 the adjacent vertical edge may be cut away, as indicated at 70, in Figure 6, so that the adjacent vertical edge of the end wall 14 will clear the inner side of the adjacent cleat 35 or flange 16 of the side wall 11. The bottom wall 13 is provided adjacent the opposite ends and inwardly from the bottom cleats 16 with inner blocks 71 which are secured by fastening members 72 to the bottom wall 13 inwardly from the adjacent cleat 16. The end wall 14 is adapted to engage between the block 71 and the adjacent inner side of the bottom cleat.

In the assembly of the box, the opposite side walls 11 may be raised to a vertical position with the lower edges of the side walls 11 resting on the inner sides of the bottom wall 13, as shown in Figure 4. The end walls 14 may then be inserted between the block 71 and the end cleat 16 secured to the bottom wall 13, and the pintle 69 of each hinge is then inserted in the aligning barrels of the hinge sections 65 and 66. It will be assumed at this time that the top wall 12 is completely detached from the side walls by removal of the pintles 60. The container may then be filled with the desired material and where this material is to be compressed, the container may be put in a form which will prevent breaking of the container under the compressing force. After the material has been compressed to the desired degree, the top 12 may be secured in place by replacing the pintles 69.

When it is desired to collapse the container, the pintles 60 on one edge of the top wall 12 may be removed and one pintle 69 of each pair of hinges 64 may be removed. The top, side and bottom walls may then be laid out flat, as shown in Figure 7, and at this time the end walls 14 may be swung inwardly, as shown in Figure 7. One end wall 14 will be swung inwardly against the inner side of one side wall 11 with only one upper hinge as a pivot, and the other end wall 14 will be swung inwardly with the remaining hinge as a pivot. If desired or if the container in collapsed form is too long to be conveniently shipped as laid out in Figure 7, the top and one

side wall 11 may be swung in overlying position to the bottom and the other side wall 11, the top 12 resting on one side wall 11 and the other side wall 11 resting on the outer side of the bottom wall 13.

In Figure 9 there is disclosed a modified form of end wall, generally designated as 73. This end wall 73 is constructed of a pair of vertical boards 74 having secured thereto upper and lower horizontal boards 75 and 76, respectively, and intermediate horizontal boards 77. The boards 77 are spaced from the upper and lower boards 75 and 76 so as to provide a perforate or slatted end wall. The several boards making up the end wall 73 are firmly secured together by means of nails or other fastening members 78. It will be understood that the modified form of end wall shown in Figures 8 and 9 will have secured thereto the upper hinge sections 65 for detachable connection with the hinge sections for the end walls which are carried by the side walls 11.

The container hereinbefore described is constructed as a collapsible container which in collapsed form can be readily returned to the shipper with the container in its collapsed form occupying only a minimum amount of space. The return charges for freight on the collapsed container are relatively smaller so that the use of this collapsed container will be practical and economical to a shipper.

Furthermore, the use of this collapsible container will be economical as a container of this type can be very sturdily built in order to withstand rough handling when either filled or in collapsed form. In addition, the construction of a container of this type out of plywood will greatly reduce the weight of the container itself and thereby reduce the return freight charges. As will be noted from Figure 7 of the drawings, the various parts of the container are firmly held together when the container is in collapsed form with the only exception of the two pintles for

the disconnected hinge sections for the two end walls. In other respects all of the parts of the container will be held together when the latter is in collapsed form thereby assuring the reassembling of the complete container when it has been returned to the shipper.

It will, of course, be understood that various materials may be placed in this container, and where the materials require, the container may be made with perforate end walls, or in other instances, the end walls may be imperforate. As an example, the container may be used for shipment of tobacco which may be compressed into the container, or the container may be used for minerals or other loose material.

What I claim is:

A collapsible container comprising top, bottom, opposite side and opposite end walls, inwardly projecting cleats at the opposite ends of said top, bottom and side walls, said end walls abutting against the inner faces of said cleats, a pair of blocks secured to the inner face of said bottom wall inwardly of said cleats and adapted to abut against the inner faces of each of said end walls to thereby hold said end walls against inward movement, each end wall being secured to the opposite side walls only by a pair of detachable hinge members having pintles securing the upper end portion of each end wall to the inner faces 30 of said side walls whereby removal of the pinte of one hinge will permit swinging of an end wall against the opposite side wall, each end wall having the outer vertical edge thereof cut away whereby said end wall may be swung inwardly 35 against an adjacent side wall, and means hingedly securing said top, bottom and side walls together, said hinge means including inwardly projecting barrels thereby providing smooth outer surfaces, said side and top walls being formed with recesses within which said barrels are adapted to engage.

RALPH S. McCONNELL.
